UNITED STATES PATENT OFFICE

112,980

DESIGN FOR A DRESS ENSEMBLE

Christine Mazola, New York, N. Y.

Application November 29, 1938, Serial No. 81,446

Term of patent 3½ years

To all whom it may concern:

Be it known that I, Christine Mazola, a citizen of the United States and a resident of the city of New York, in the county of New York and State of New York, have invented a new, original, and ornamental Design for a Dress Ensemble, of which the following is a specification, reference being had to the accompanying drawing, constituting a part thereof:

Fig. 1 is a front view of a dress ensemble showing my design.

Fig. 2 is a rear view thereof.

Fig. 3 is a front view of the dress section of the ensemble shown in Fig. 1.

Fig. 4 is a rear view of Fig. 3.

The characteristic feature of my dress ensemble resides in the arrangement of the graduated nail heads on the lapels of the jacket and the upper waist of the dress in association with the dress and jacket as shown.

I claim:

The ornamental design for a dress ensemble, substantially as shown and described.

CHRISTINE MAZOLA.
